PACKAGE AND PARTS THEREOF FOR
DELICATE ARTICLES

Charles D. Verde, Union City, N. J.

Application September 30, 1949, Serial No. 118,929

1 Claim. (Cl. 206—18)

1

The present invention relates to packaging and more particularly to a package adapted to contain and protect against injury of delicate or easily injured watch parts, assemblies, or the like.

The problem of containing and shipping items such as small watch parts or assemblies is particularly troublesome due to the fragile or delicate nature of the items or assemblies. For example, in connection with the repairing of watches the jeweler who receives the watch frequently sends the balance wheel-bridge-hairspring sub-assembly to a specialist for checking and calibration, as these specialists possess the necessary equipment and special skills required for such work. After being repaired and calibrated such delicate assemblies must be returned to the jeweler for reassembly by him into the watch from which it was removed.

By reason of the very delicate nature of such assemblies it has been necessary to exercise extreme care in handling them during return to the jeweler. Since no satisfactory means has heretofore been provided for satisfactorily holding the very delicate and finely adjusted assemblies it has previously been the practice to disassemble and separately wrap some of the components and to then return them to the jeweler, the latter being obliged to reassemble the components and recheck them.

This previous practice has been highly objectionable in view of the original repair, calibration, disassembly, individual wrapping of the parts, shipping, and subsequent reassembly and recalibration. In the subsequent reassembly and recalibration one or more of the parts has frequently become damaged sufficiently to require again sending it to the specialist for subsequent repair and recalibration. The foregoing procedure has been time-consuming, laborious, tedious and unduly expensive. There have been devised various containers for holding watches but in those instances the delicate parts are usually embodied in their working position in the watch and therefore subjected to conditions similar to those arising during wearing of the watch by an individual; even in those instances, however, some of the packages have been unduly complicated by reason of requiring special spring mounting, etc.

The present invention aims to provide a new and improved package comprising an outer casting or container with interior packing or cushioning material for holding delicate watch parts in position against injury.

An object of the present invention is to provide a new and improved package.

2

Another object of the invention is to provide a new and improved package adapted to contain delicate watch parts in an assembled condition during shipment thereof.

5 Another object is to provide a new and improved packing for holding delicate parts in position in a container.

Another object is to provide an improved package adapted to contain delicate parts which is of 10 relatively simple and inexpensive construction.

Other and further objects of the invention will be obvious upon an understanding of the illustrative embodiment about to be described, or will be indicated in the appended claims, and various 15 advantages not referred to herein will occur to one skilled in the art upon employment of the invention in practice.

A preferred embodiment of the invention has been chosen for purposes of illustration and 20 description and is shown in the accompanying drawings, forming a part of the specification, wherein:

Fig. 1 is a sectional view showing the present package prior to application of the cover portion;

25 Fig. 2 is a cross sectional view through the present package with the cover in closed position and showing an article held in position;

Fig. 3 is an exploded perspective view showing the parts of the present invention;

30 Fig. 4 is a side elevational view showing a packing or cushioning member of the present invention;

Fig. 5 is a perspective view showing a member similar to that of Fig. 4 with one side spread apart to more clearly disclose the interior construction 35 thereof;

Fig. 6 is a sectional view illustrating in general one method of forming the packing or cushioning members such as illustrated in Fig. 4;

Fig. 7 is a side elevational view showing a modified form of packing or cushioning member; and

Fig. 8 is a perspective view of the member shown in Fig. 7.

In Figs. 1 through 5 there is shown a preferred 45 embodiment of the present invention. As there shown the present device comprises a hollow receptacle 1 having a bottom portion 2 and upwardly extending side walls 4, the latter being provided with a laterally extending projection or 50 bulge 5. The receptacle 1 may be of generally circular shape and the bulge may comprise an annular protuberance extending around it. A lid or top member 7 adapted to cooperate with the receptacle 1 has a cover portion 8 and downwardly extending side walls 9, the latter being 55

of interior diameter to fit closely over the upper portions of the side walls 4 and to rest at the lower end or edge 3 thereof against the outwardly extending bulge or protuberance 5. The protuberance 5 thus serves to limit the extent of downward movement of the cover 8 toward the bottom 2. Together, the top member 7 and receptacle 1 form a hollow container which is adapted to hold the new and improved packaging or cushioning material about to be described. This packaging material serves to retain a delicate watch part or sub-assembly 11 in position within the container.

As shown in Fig. 2, the delicate watch part or subassembly 11 is supported between upper and lower thicknesses of cushions 13 and 14, these thicknesses being separated from each other by layers of material 16 and 17. Each thickness or cushion 13 and 14 preferably comprises a plurality of layers 19 of cellulose wadding, the several separate layers being joined or interlocked with each other at their outer edges but having layer portions disposed inwardly of their outer edges free of interlocking engagement.

The construction of one of the thicknesses or cushions is illustrated more particularly in Fig. 5 where one of them is shown pulled apart at one side or edge thereof. Preferably each layer of material is of a filmy or loose fibrous nature; that is, each layer is relatively thin and delicate with numerous openings through it. While any suitable number of layers may be joined together, depending to a certain extent upon the degree of compressibility or softness desired, seventeen to twenty such layers will give good results in holding a watch sub-assembly comprising a balance wheel, bridge and hairspring.

To form the thickness or cushions shown in Figs. 1 through 5, a plurality of layers of loose fibrous cellulose wadding material may be moved beneath a reciprocating punch 22 (Fig. 6) which "knocks out" a completed thickness or cushion at each down stroke. As the punch 22 descends, it compresses the separate layers of material 19 adjacent the outer edges of the punch and seems to firmly squeeze them into interlocking relationship adjacent the outer edges of the punch, between the outer edges 23 of the punch and a cooperating edge 24 of a die 25. Reciprocation of the punch 22 thus compresses and cuts out a cushion at each down stroke. The edges of the material are firmly interlocked or joined together along marginal edges 28 and the interlocked edges 28 retain the separate layers securely together as a unit. It is not necessary to use glue or adhesive for holding the marginal or edge portions together as the operation of stamping the disc-like thicknesses 13 and 14 out of the multiple layers of material 19 seems to squeeze them and interlock them together sufficiently to retain their shapes and to prevent separation into individual layers under normal conditions of usage. Centrally disposed portions 31 and 32 of the thicknesses bulge or curve outwardly apart from each other and away from the marginal edge portions 28 to thus provide a very soft or yielding construction with contiguous separate layers of material. The cushions or thicknesses 13, 14 are thus particularly soft and yieldable adjacent their mid-portions.

The relative proportions of the container and the cushions are such that when two cushions are placed within a receptacle 1, they project above it (Fig. 1). In addition, peripheral portions of the cushions preferably lie closely ad-

jacent the interior side walls of the receptacle 1. Thus when the top 7 is placed onto the receptacle 1, the cover portion 8 presses downwardly against protruding portions of the cushions and presses them, particularly their mid-portions, toward each other.

When used for holding a delicate watch sub-assembly such as the bridge-hairspring-balance wheel unit, illustrated in Fig. 2, the upper and lower cushions 13 and 14 are preferably separated from each other by the layers of material 16 and 17. These layers preferably comprise some substantially lint-free material such as tissue paper, which serves to keep lint or minute particles of cellulose wadding from getting into the hairspring or other parts of the unit 11.

Assembly of the parts will now be described more particularly with reference to Fig. 3. A lower cushion member 14 may be first placed into position at the lower part of the receptacle 1 and thereafter a layer of tissue paper or other suitable material 17 may be laid against the upper surface of the cushion 14. The delicate watch unit or sub-assembly to be contained or shipped through the mail is then laid upon the upper surface of the tissue layer 17. The upper layer of lint-free material or tissue paper 16 is then placed over the watch unit and thereafter the upper cushion 13 laid upon the uppermost surface of the tissue layer 16. Finally the top member 7 is placed over the uppermost surface of the thickness or cushion 13 and aligned with the side walls 4 of the receptacle 1, in which relationship it may be pressed gently "home" upon the receptacle. As the cover portion 8 of the top 7 moves toward the bottom 2 of the receptacle 1 the cushions or thicknesses 13 and 14 are compressed toward each other; their portions which are disposed laterally outwardly beyond the article 11 (Fig. 2) to be held approach each other and press into contact with each other the outwardly disposed portions of the tissue paper layers 16 and 17. Thus, those portions of the tissue paper layers 16 and 17 and of the cushions 13 and 14 which are disposed generally around the borders of the article to be retained are moved toward each other so as to enclose or surround the article.

Those portions of the tissue layers and of the cushions which are more centrally disposed yield outwardly as the cushions 13 and 14 are pressed together, this being effected by the article 11 which is retained; note the relationship of the cushion members, tissue layers, and watch sub-assembly 11 as shown in Fig. 2. Lint or minute fibrous particles are kept out of the delicate mechanism 11 by the tissue layers 16 and 17; it will be clear that other suitable material than tissue paper may be used for these layers 16 and 17. The watch "unit" or part is thus held gently but firmly against either up and down or lateral movement by the cushions which "fold" together around it. The cushions themselves are, of course, similarly held against up and down or lateral movement by the top and bottom of the container and by the side walls thereof, the cushions being preferably in contact with the side walls of the receptacle or container as well as with the top and bottom of it.

In Figs. 7 and 8 there is shown a slightly modified form of cushion member 34 which may be desired in some instances. The cushion member there shown differs from that of the preferred embodiment in that it has a sort of peripheral flange 35 which is adapted to lie closely adjacent

interior walls of a container such as that shown in Figs. 1, 2 and 3.

It will be seen that the present invention provides a new and improved package which is adapted to contain delicate watch assemblies or individual parts. The parts or assemblies are firmly but gently supported upon yieldable cushions and out of contact with any rigid walls or portions which might serve to damage them during shipment or otherwise. The delicate or fragile parts are firmly retained within a container against movement in any direction therein under normal conditions of usage. The present new and improved package is of relatively simple and yet inexpensive construction; it provides for shipment of such delicate parts through the mails by merely enclosing it within a mailing envelope. The present new and improved package obviates the necessity for disassembling a repaired and calibrated unit, individually wrapping the parts and shipping them through the mail, subsequently unwrapping and reassembling the parts, and thereafter rechecking to be sure that none of the parts has been damaged during shipment. As a result a great amount of time, labor and expense is saved.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

A package of the class described comprising co-operating bottom and top receptacle members having interfitting telescopic side wall portions, in combination with a pair of like preformed self-

sustaining cushion elements each relatively loosely contained within one of said members, each of said elements comprising a plurality of layers of soft, cellulose, fibrous, tissue-like sheets having their central areas unattached to each other and crowned to provide a bulging zone of high compressibility and softness and having their outer margins adhering together with the fibers of the sheets interlocked in a compressed state to provide a relatively narrow and thin perimetric edge flange that is relatively hard and stiff and substantially engages the side wall portions of the respective member, whereby the bulging central zone is compressed by the members to yield about an article and the stiffness of the edge flange resists lateral deformation of the cushion element on the imposition of pressure from the side walls of the members.
